UNITED STATES PATENT OFFICE.

ELISHA H. TOBEY, OF ST. LOUIS, MISSOURI, ASSIGNOR TO HIMSELF AND ST. LOUIS RAILWAY SUPPLIES MANUFACTURING COMPANY, OF SAME PLACE.

IMPROVEMENT IN DRAW-BRIDGE SAFETY SWITCHES AND SIGNALS.

Specification forming part of Letters Patent No. 140,319, dated June 24, 1873; application filed January 10, 1872.

To all whom it may concern:

Be it known that I, ELISHA H. TOBEY, of the city and county of St. Louis and State of Missouri, have invented certain Improvements in Draw-Bridges and Railway Signals and Switches, of which the following is a specification:

My invention consists in the combination of the bolt by which the draw of a draw-bridge is secured, with a switch by which the train may be directed onto a side track if the draw is not in position to receive it.

Figure 1 is a perspective view of my improvement. Fig. 2 is a plan of a part of the same, both figures representing the draw as closed and locked in position.

A is one end of a draw, and B the framework supporting the railway track b, against which the track a of the draw abuts when the draw is closed. C is the bolt-keeper attached to the draw. D is the draw-bolt, having upon its side a rack, d, engaging a spur-wheel, e, on the turn-staff or shaft E, which is turned by a hand-wheel, F. At the upper end of this staff is a signal-lantern, G, having two red glasses, g, and two green glasses, g', indicating safety to the road and danger to the river, or vice versa. A one-fourth rotation of the wheel F serves to withdraw or shoot the bolt E, and to reverse the indication of the signals. Upon the staff E is a crank-arm, e', connected by a rod, h, to a similar crank-arm, h', upon the staff H of the signal-lantern G', similar to G, and having similar movement by means of the cranks and rod e' h' h', the two signals turning simultaneously. I is a pulley or sheave on the turn-staff E, to which is firmly attached a wire or wire rope, i, that is also attached to the sheave J upon the combined switch and signal-staff K, which has at the lower end a crank-arm, k, by which any ordinary switch may be operated. L is a lever by which the staff K may be turned and the switch worked independently when disconnected from the draw-bolt. The lever L turns in a horizontal plane, and rests on a semicircular guide-bar, l, to which it may be locked or secured in any

position. At the upper end of the staff K are day and night signals, consisting, respectively, of arms M and a lantern, N, firmly attached together and to the staff, so as to turn with certainty therewith and with each other. The signal-lantern N always shows the same signals as those, G G', viz: A green light in the direction of the railway track when the draw is closed, and a red light when the bolt is drawn out. The turn-staff K is supported in brackets extending from a post, o, that may be made of considerable height and have an elevated platform, P. The signals M N may be at a distance of half a mile, more or less, from the draw, so as to allow ample time for the engineer to govern himself by the signal. When carried any considerable distance, the wire or wire rope i passes over sheaves or other supports.

By the application of my improvements accidents at draw-bridges may be avoided, as the draw-bolt cannot be drawn out without exhibiting the danger-signals G G' M N, and at the same time operating, by means of the switch-lever k, a switch at the signal-post o to run off the train upon a side track when the draw is not secured.

The special advantage, in addition to the saving of time, of operating the near and distant signals simultaneously with the draw-bolt, is that resulting from certainty of action, as the draw cannot be at any time opened without the railway danger-signals being shown, nor closed without signaling danger to the river.

What I claim as my invention, and desire to secure by Letters Patent, is—

The draw-bridge bolt D and switch-arm k for operating the switch, located at a considerable distance apart, in combination with the connections e E F l i J K, for operating one from the other, as explained.

ELISHA H. TOBEY.
